HERMAN A. SPERLICH AND JOHANNES H. UHLIG, OF HIGHLAND PARK, MICHIGAN

CONTROL FOR IRONING MACHINES

Application filed May 10, 1932. Serial No. 610,479.

This invention relates to ironing machines following description and the accompanying drawings in which
and more particularly to thermostatic controls for the heaters of machines wherein the
shoe is heated, and it will be understood that
5 the control shown may be utilized with various forms of shoe heaters, such as gas
burners, electric coils, etc.

In the application of Herman A. Sperlich
and Johannes H. Uhlig, Serial No. 46,958,
10 filed July 30, 1925, there is disclosed an ironing
machine having a base, a vertical frame
member supporting a horizontal roll, and a
second vertical member supporting an elongated
5 horizontal shoe disposed adjacent the
roll. The second frame member or leg is inter-
mediate the ends of the shoe so that these
ends are free. In the said application the shoe
heating means includes electric heating units
15 to which lead conductor wires disposed in the
shoe supporting leg. In the ironing machine
shown in this application, gas burner pipes
are disposed in the shoe adjacent the under
surface thereof, and are connected to a vertical
20 gas supply pipe, disposed in the vertical
shoe supporting leg, there being a control
valve in the pipe, controllable by means of a
thermostatic control which forms a major
part of the invention of this application.

An object of the invention, therefore, is an
ironing machine having an elongated horizontal
shoe supported by a vertical leg in such
a manner as to have at least one free end,
gas burner pipes under the shoe, fed by a
vertical pipe in the leg, and a control valve
35 in the gas supply line controllable by a ther-
mostatic control.

A further object of the invention is an ironing machine having gas heating means
40 controlled by a control valve in the supply
line, resilient means tending to keep the valve
closed, personally operable means for opening
the valve and thermally controlled means
45 for permitting the valve to close in accordance
with the rising temperature of the shoe.

Still further objects are novel forms of
parts for use with the combination described
in the foregoing paragraph.

Still further objects will readily occur to
50 those skilled in the art upon reference to the

Figure 1 is a partial section view of the
shoe and the appurtenant parts taken from
the left of Figure 5.

Figure 2 is a face view of the control valve
and is taken in the direction of the arrow 2
of Figure 1.

Figure 3 is a face view of the setting plate
and pointer and is taken in the direction of
the arrow 3 of Figure 1.

Figures 4 and 5 are sections on the lines
4-4 and 5-5 of Figure 1.

Figure 6 is a small scale view of the shoe
and its supporting leg, provided with the
control of the invention.

Referring to the drawings, it will be observed
that the ironing machine, only part
of which is disclosed, includes a base 10 having
a vertical hollow leg 12, upon which is
supported the elongated horizontal shoe 14,
the latter being adjacent the horizontal roll
15. As seen best in Figure 6, the leg is inter-
mediate the ends of the shoe and the latter
has two free ends, to one of which one end
of the control mechanism is adjustably se-
cured. Under the shoe is a shoe guard 16
upon which is supported an elongated burner
pipe 18, the latter being disposed between
the shoe and the shoe guard. A vertical sup-
ply pipe 20 leads to the burner pipe and is
disposed in the leg 12. Gas from the supply
line 22 passes thru the control valve 24 and
into the mouth of the supply pipe 20 thru an
adjustable nipple 26, the pipe having side
openings or ports 28, for air which is to mix
with the gas from the pipe 22. The degree
of opening of the valve 24 is controlled man-
ually and also by the thermostatic control
means forming a major part of the invention.
The same will now be described.

The under surface of the shoe, near one of
its free ends, is provided with an integral
boss 30 having a hole 32 into which is in-
serted the pin end 34 of a cast setting plate
or dial 36, there being a set screw at 38 for
securing the plate 36 on the boss and conse-
quently on the shoe. One of the faces of the
setting plate is provided with markings,
Figure 3, and the setting plate is further

provided with a tapped hole 39 thru which is threaded the screw 40. Threaded on the free end of the screw is the setting pointer 42 and a lock nut 44 secures the setting pointer fixedly in place on the screw 40.

There is thus formed for the setting pointer 42, a journal in the plate 36, so that the pointer may be rotated about the setting plate for purposes to be described later. A ball check 46 in the pointer frictionally restrains the pointer from moving except in accordance with the will of the operator of the machine.

The end of the screw 40 most remote from the pointer is provided with a cavity 50 which receives an elongated link or rod 52 of invar steel, this material being selected because it has a much smaller coefficient of expansion than the material of the shoe itself, which is preferably of cast iron. The other end of the rod 52 is connected to a bell crank 54, the latter being pivotally fixed to the shoe by a pin 56 passed into a boss on the under surface of the shoe, similar to the boss 30. The other arm of the bell crank 54 is pivotally connected at 58 to a link 60, also of invar steel, which in turn is pivotally connected at 62 to a bell crank 64, the latter being pivotally fixed at 66 to the cap 68 of the valve 24. The cap is bolted to the body by bolts 70, thereby clamping between it and the body, a flexible normally bowed diaphragm 72 to which is secured the valve closing member 74, the securing means including a cap nut 76 extending beyond the cap 68. The body of the valve 24 is provided with a valve seat 78 adapted to be closed by the closing member 74. A coiled tension resisting spring 80 is secured to the bell crank 64 at 82, and is secured to a pin 84 fixedly mounted on the base of the machine in a suitable manner.

The operation of the device will readily be understood from the foregoing. When the operator desires to have the machine heated to a temperature, let us say, 300 degrees, he rotates the setting pointer 42 until it is on the 300 mark. This action takes up the lost motion between screw 40 and rod 52 and causes the screw 40 to push upon the invar steel rod 52, lifting the link 60 and rotating bell crank 64 clockwise, Figure 1, on its pivot 66, against the tendency of the valve closing spring 80. When the bell crank 64 is lifted off the cap nut 76, Figure 1, the diaphragm 72 is permitted to bow outwardly to its fullest extent, and the closing member 74 will move away from the valve seat 78, opening the valve 24. Gas will then flow to the supply pipe 20 and will burn, being ignited by a pilot, which is not shown or described but which may be provided in any suitable manner. The shoe will heat considerably until it reaches the desired temperature. During this heating the shoe will tend to expand, that is to say, its free ends will move away from

the leg 12. Accordingly, the setting plate 36 and the screw 40 will move to the right, Figure 1, relieving the force on the right hand end of the rod 52, which has not expanded as much as the shoe because of its low coefficient of expansion. The spring 80, meanwhile pulling upon bell crank 64, will tend to close the valve 24 as much as is permitted by the control mechanism, the movement being checked by the engagement of the right hand end of the rod 52 with the end of its seat 50 in the screw 40.

It will be seen that when the shoe reaches the desired temperature the gas supply is checked to the necessary degree. If, after the shoe has become heated to a considerable temperature, it is desired to lower the temperature, the setting pointer is turned backwardly, pulling the screw away from the rod 52 and permitting the spring 80 to close the valve even further.

One of the important features of the invention is the specific construction of the valve operation means. It will be seen that the valve can open only to a limited extent regardless of the setting of the pointer. Accordingly, no matter how much the crank 64 is elevated or moved away from the cap 68, the valve will open no more than to its full open position as determined by the flexing of the diaphragm 72. The stress will, therefore, be upon the spring 80 which is readily replaceable, and not upon the diaphragm 72 whose original calibration is never injured or unduly stressed.

It will further be seen that the shoe itself acts as the prime mover for the thermostatic control and accordingly a direct operative connection between the temperature of the shoe and the degree of opening of the valve is created.

It will further be seen that the connection between the rod 52 and the setting pointer is of the lost motion type and that this lost motion is taken up by the spring 80 or by the manual adjustment of the setting pointer, or by the contraction of the shoe.

It will also be observed that the thermostatic control shown may be utilized in connection with electrically heated ironing machine shoes. For example, the gas burners may be replaced by heating coils and the control valve may be replaced by a controlling rheostat.

It will further be observed the invention is of value in connection with other forms of material processing means, wherein a heat-processing member may correspond to the shoe 14, and a material feeding member corresponding to the roll 15.

It will further be observed that while in the machine shown the shoe is under the roll, the invention may well be used in machines wherein the shoe is above the roll, if desired. Further, instead of, or in addi-

tion to the shoe being heated, the roll might be heated, if desired.

It will also be noted that restraining means other than the ball check 46 might well be used for the indicator or setting pointer or handle 42. For example, the screw 40 might have its threaded portion split and spread in the tapped hole 39 of the setting plate 36 to provide a friction check for the handle 42.

10 It will further be noted that if desired a gas pressure regulator might well be used in the gas line.

Further, it will be noted that the shoe 14 is provided with two series of vent holes 15 90-92 near and along its upper edge. One series opens to the upper surface of the shoe and normally provides a sufficient path for the escape of the products of combustion from the burners. This series of holes may, 20 however, be covered or smothered by material such as a heavy blanket, etc., fed to the machine and lying over this series of vents. Accordingly, the second series is provided, this series venting the burners even 25 when the first series is completely closed.

Now having described the invention and the preferred embodiment thereof, it is to be understood that the said invention is to be limited, not to the specific details herein 30 set forth, but only by the scope of the claims which follow:

What we claim is:

35 1. In an ironing machine, a substantially vertical leg, an elongated horizontal shoe

supported on said leg and having a free end, burners for said shoe, a gas supply line in said leg and leading to said burners, a valve in said leg for said supply line, means tending to close said valve, a plate fixed to said shoe, adjacent the free end thereof, a setting pointer journaled in said plate, and a link of less expansibility than and disposed parallel to said shoe, the link being operatively connected, at one end to said valve, and at 75 the other end, to said setting pointer by a lost motion connection, whose lost motion can be taken up by manual adjustment of said pointer or by contraction of said shoe.

2. In an ironing machine, a substantially vertical leg, an elongated horizontal shoe supported on said leg and having a free end, burners for said shoe, a gas supply line in said leg and leading to said burners, a valve in said leg for said supply line, means tending to close said valve, a plate fixed to said shoe near the latter's free end, a setting pointer journaled in said plate, a bell crank pivotally mounted on said shoe, near the leg, a horizontal link of less expansibility than said shoe connected at one end to said bell crank and at the other end to the pointer by a lost motion connection whose lost motion can be taken up by movement of the pointer or by contraction of the shoe, and a vertical link 90 connecting said bell crank to the gas supply valve.
